[57] CLAIM

The ornamental design for a fishing plug, as shown and described.

DESCRIPTION

FIG. 1 is a side elevational view of a fishing plug showing my design;

FIG. 2 is a front elevational view of the plug shown in FIG. 1;

FIG. 3 is a top plan view of the plug;

FIG. 4 is a bottom plan view thereof;

FIG. 5 is an elevational view taken from the trailing end of the plug;

FIG. 6 is a perspective view of the plug;

FIG. 7 is a side elevational view of a modified form of the fishing plug shown in FIGS. 1 through 6;

FIG. 8 is a front elevational view of the plug shown in FIG. 7;

FIG. 9 is a top plan view of the plug shown in FIG. 7;

FIG. 10 is a bottom plan view of the plug shown in FIG. 7;

FIG. 11 is an elevational view taken from the trailing end of the plug shown in FIG. 7; and

FIG. 12 is a perspective view of the plug shown in FIG. 7.

FIG. 1.
